INDUSTRIE-GESELLSCHAFT M. B. H., OF BERLIN, GERMANY.

TYPE SETTING AND CASTING MACHINE.

No. 918,739.

Specification of Letters Patent.

Patented April 20, 1909.

Application filed November 9, 1906. Serial No. 342,674.

To all whom it may concern:

Be it known that I, HEINRICH DEGENER, a subject of the King of Prussia, German Emperor, and resident of 26 Hollmann street, Berlin, Germany, manager, have invented certain new and useful Improvements in Type Setting and Casting Machines, of which the following is an exact specification.

This invention relates to type setting machines and has particular reference to the spacing mechanism.

In U. S. Patent No. 605,141 the spacing devices shown frequently do not fall correctly into position with their shoulders in a proper position in the carrying rule and thereby a spacer was rendered inoperative and was damaged when the line carriage entered the anvil of the molding mechanism.

The present invention remedies the above drawbacks by causing the spacer when not properly in position to render a stopping device for the machine operative. A suitable arrangement is hereby described with reference to the accompanying drawings, in

which:

Figure 1 of the accompanying drawings shows the device seen from the righthand side of the machine; Fig. 2 shows it in plan, Fig. 3 seen from the front, and Fig. 4 illustrates the release of the mechanism by a space.

The device consists of a releasing pawl *a* secured to the spindle *b* and rotatably arranged with the same in bearings *c*. At the other end of the spindle *b* is arranged a locking pawl *d* which can engage with its finger *e* under the projection *f* of the block *g* (Fig. 3). The block *g* is vertically movable on pins *h*. In the drawing it is shown in its lowest position in which it rests on the table plate. The highest position of the same is shown by dotted lines in Figs. 1 and 3. In the block *g* is arranged a slide *i* provided at its back end with a roller *k*. On one of the cams driving the separate mechanisms of the machine in the drawing for instance, on the curve for moving the line carriage, is mounted a plate *l* in such manner that, when the cam rotates, it strikes with its oblique face *m* against the roller *k* and thus brings the slide *i* out of its position of rest. If the block *g* is in its upper position, the slide, as can be seen in Fig. 3,

can move freely toward the right, and after the plate *l* has passed, is brought back again into its original position by the spring *n*.

As is well known, the machines of the monoline system are provided with a device which makes it possible instantaneously to stop the machine at any moment. The coupling of the machine with the counter-shaft is effected, as shown in the drawing, by means of a clutch coupling *o*, one half of which is connected by a pin to the releasing bolt *p*. If the bolt *p* is pressed, the halves of the clutch become disengaged and the machine stops. Against the releasing bolt *p* rests a lever *q* (see Fig. 2) rotatably mounted about *r* and provided at the bottom with a roller *s*. If it is desired to stop the machine, the slide *u* (Figs. 1 and 2) is moved toward the right by a lever, not shown in the drawing, by means of a connecting rod *t*. The slide *u* strikes with its front obliquely cut off face *v* against the roller *s* and thus moves the lever *q* which again disengages the clutch by pressing the bolt *p* inward. If the slide *u* is again withdrawn, the halves of the clutch are again brought into engagement by means of a spring not shown in the drawing, and the machine continues to rotate. When the block *g* is in its lowest position (Fig. 3) the slide *i* engages with its correspondingly shaped front end *w* either direct or by means of any desired intermediate members with the lever *q* and when moved by means of the plate *l* toward the right, carries with it the said lever *q* whereby the machine is at once stopped, as will be clear from the preceding description.

Under the table plate is arranged a spindle 2 provided at both sides with small levers 3 and 4. The lever 3 rests with its point against the pin 5 arranged at the bottom in the block *g* and projecting below the table plate through a hole in the same. The second lever 4 is connected by means of a rod 7, the length of which is adjustable by means of a screw 6, to the connecting rod *t*, so that, when the latter is moved forward 100 the spindle 2 is rotated, and the block *g* raised by means of the lever 3 and the pin 5.

The working of the device is as follows: During normal working of the setting ma-

chine the spaces α drop so that their noses α' enter and travel in the groove formed by the rule g^1 and the covering bar z' (Fig. 4). The spaces can then freely pass the pawl a .
 5 If, however a space drops with its nose above the covering bar, as shown in Fig. 1, then when the said space is moved farther, its finger strikes the releasing pawl a and rotates the spindle b . In this way the projection e of the locking pawl d which, in the position of rest, is under the projection f of the block g and keeps it raised, is pulled away from under the said block which falls by gravity, which may however be assisted 10 by a spring. Then the slide i comes to rest with its front end w against the lever q . When the cam rotates and the plate l comes against the block, it will move the roller k and with it the slide i and the lever q toward the right by means of its oblique face m (Fig. 3). The lever q in its turn presses 15 against the releasing bolt p and thus at once stops the machine. The compositor now has time to remove the space projecting 20 too high and to replace it by a hand space. If the machine is to continue to work, then the compositor throws it into gear in the usual manner, that is to say, he moves the slide u forward by means of the connecting rod t . At the same time the rod 7 and the lever 3 turn the spindle 2 , so that the lever 3 arranged at its other side, presses against the pin 5 and raises the block g . As soon 25 as the latter has been sufficiently raised, the finger e which is constantly pressed by the spring 8 against the projection f of the block g , springs under the latter and keeps it in its raised position. The machine can then run. If all the spaces have fallen 30 down properly, that is to say, if the stop device is not actuated, then, when the plate l presses against the roller k , the slide i reciprocates with its back end above the lever q as shown in dotted lines in Fig. 3, that 35 is to say, it does not influence the working of the machine.

The arrangement is similar in other setting machines in which justifying is done by means of similar wedge-spaces.

50 Having thus fully described the nature of my invention, what I desire to secure by Letters Patent of the United States is:—

1. In type setting machines in combination a spacer and guide rule along which said spacer moves, means coöperating with an improperly placed moving spacer for stopping the machine.

60 2. In a type setting and line casting machine, the combination of a spacer having a shoulder thereon, a guide rule along which said spacer moves, a cover plate over said guide rule, said cover plate and guide rule being adapted to receive the shoulder of the spacer and forming a guide groove therefor,

and means coacting with a moving spacer 65 whose shoulder lies outside the guide groove for stopping the machine, substantially as described.

3. In combination with type setting and casting machines a matrix holding rule, 70 spacers adapted also to be held by said rule, shoulders on said spacers, by which they are held, means operated by said shoulders, when they are not in proper position in the rule for stopping the machine. 75

4. In type setting machines, in combination a spacer, a guide rule along which said spacer moves, means coöperating with the moving spacer improperly placed on the rule for stopping the machine and means for re- 80 starting the machine.

5. In combination with a type setting and casting machine justifying mechanism comprising wedge pieces supplied to the line to be justified, shoulders on said wedge pieces, 85 a holding rule, destined to receive said shoulders, a projection in the path of said shoulders when not in proper position in the rule, means operated by the consequent motion of the projection for stopping the machine. 90

6. In combination with a type setting and casting machine justifying mechanism, comprising wedge pieces supplied to the line to be justified, shoulders on said wedge pieces, a holding rule destined to receive said shoulders, a rotating cam, a block having a sliding member therein operated by said rotating cam, supporting means for said block, a projecting part associated with said supporting means and entering into the path of those 100 shoulders on the justifying wedges, which are not in proper position in the rule and co-operating with said shoulders for releasing the block, means operated in the changed position of the slide on the block for stopping 105 the machine.

7. In combination with a type setting and casting machine justifying mechanism, comprising wedge pieces supplied to the line to be justified, shoulders on said wedge pieces, a holding rule destined to receive said shoulders, a rotating cam, a block having a sliding member therein operated by said rotating cam, supporting means for said block, a projecting part associated with said supporting means and entering into the path of those shoulders on the justifying wedges which are not in proper position in the rule and co-operating with said shoulders for releasing the block, means operated in the changed position of the slide on the block for stopping 110 the machine, means for restoring said block to its original position when a spacer has been righted. 115

8. In a monoline and like type casting machine means for stopping the machine when a justifying spacer is in incorrect position comprising an arm a operated by incorrectly 120

placed spacers, a supporting arm *d* operated simultaneously with the arm *a*, a block *f* supported by said supporting means, a slide *i* carried by said block, a cam *e* operating said slide, an arm *y* carried by said slide and having a free path of motion in the supported position of the block, a clutch disengaging member *q* in the path of the arm *y* when the

block is not supported in its elevated position, substantially as described.

In witness whereof I have hereunto set my hand in the presence of two witnesses.

HEINRICH DEGENER.
